(57) **CLAIM**

The ornamental design of a spikeless water for irrigation
system collector, as shown and described.

DESCRIPTION

FIG. 1 is a top, rear, left side perspective view of a preferred
embodiment.

FIG. 2 is a top plan view of a preferred embodiment.

FIG. 3 is a bottom plan view of a preferred embodiment.

FIG. 4 is a rear elevation of a preferred embodiment.

FIG. 5 is a left side elevation (right side being mirror image)
of a preferred embodiment.

FIG. 6 is a front elevation of a preferred embodiment.

FIG. 7 is a top, rear, left side perspective view of an alternate
embodiment.

FIG. 8 is a top, rear, left side perspective view of an alternate
embodiment; and,

FIG. 9 is a top, rear, left side perspective view of an alternate
embodiment.
